SLICING MECHANISM

Robert Hoe, Hyde Park, N. Y.

Application October 3, 1930, Serial No. 486,110

2 Claims. (Cl. 146—114)

This invention relates to a novel and improved slicing mechanism, the novel features of which will be best understood from the following description and the annexed drawings, in which I have shown selected embodiments of the invention and in which:

Fig. 1 is a vertical sectional view through one form of my invention, the section being taken approximately on the line 1—1 of Fig. 2;

10 Fig. 2 is a section approximately on the line 2—2 of Fig. 1;

Fig. 3 is a section on the line 3—3 of Fig. 2;

Fig. 4 is a fragmentary view, partly in elevation and partly in section, taken from the right 15 of Fig. 2;

Fig. 5 is a side elevation of the pusher used with this mechanism;

Fig. 6 is an elevation taken from the right of Fig. 5;

20 Fig. 7 is a view corresponding to Fig. 1, but showing a different embodiment of the invention, the power unit shown in Fig. 1 being omitted from Fig. 7;

Fig. 8 is a section on the line 8—8 of Fig. 7.

25 Referring first to Figs. 1 to 5, inclusive, I have shown the invention as used in combination with a power unit 1. This unit is driven from a motor shaft 2, which may be the shaft of an electric motor, part of which is shown at 3. The unit 30 comprises a gear casing from which project shafts 4 and 5. These shafts may be operatively connected together as by means of pinion 6 and a gear 7 so as to rotate at different speeds.

The casing carries hinge ears 8 on which to support devices to be operated by the shafts 4 or 5. In this instance, the device cooperates with the shaft 4 and is carried by hinge ears 9 cooperating with the pins 10 on the ears 8. This arrangement is one which holds the device in such position that its shaft 11 will be operated by the shaft 4, there being provided cooperating clutch elements 12 and 13 on the shafts 4 and 11, the shaft 11 being received in a bore in the shaft 4, as plainly shown.

40 The device may also be provided with a latch to hold it in the operative position shown in Fig. 1, one element 14 of this latch being shown in Fig. 3, it being understood that this element will cooperate with a corresponding element on the power unit.

45 A slicing mechanism is carried in a casing formed of two parts 15 and 16. These parts have their edges in contact as plainly shown, so as to form a continuous chamber in which revolves the shaft 11. The part 15 carries the ears 9 by means

of which it is supported on the power unit. The part 15 also supports the part 16, and the two parts are fastened together by means of hooks 17 engaging pins 18 on the part 15. By this arrangement of hooks, the two parts may be quickly assembled or separated by a short vertical movement of the part 16, and when the hooks are engaged, the parts are still further held together against lateral movement by means of a latch formed of a plate 19 on the part 16 which has a hole therethrough receiving a pin 20 on the part 15. Therefore, it will be seen that the two parts are rigidly fastened together and held against lateral movement, but at the same time they are quickly detachable by a very short movement of one part with respect to the other.

50 Mounted on the shaft 11 is a plate 21 having a hole 22 therethrough. On the outer face of the plate is mounted a knife 23, the plate and knife thus forming what I term a cutter. Disposed in the part 16 of the casing and on one side of the axis of the shaft 11, is a support 24 adapted to hold an article to be sliced by the cutter.

The inner edge 25 of the support is closely adjacent the cutting edge 26 of the knife, so that an article pushed past the edge 25 will engage the face of the plate 21 which thus acts as a stop, and the distance from the face of the plate to the edge 26 of the knife will define the thickness of the slice to be cut.

30 By providing, with a mechanism of this character, different plates 16 provided with different spacings of the knife edge from the plate, it is possible for the user to slice an article of food and obtain slices of varying thickness by changing the cutter. In practice, it is contemplated that a cutter unit will comprise a plate, knife and associated shaft and clutch element, so that the user may make the change with least effort.

35 The invention is primarily designed for household use and for slicing relatively elongated articles of food, such, for example, as carrots, although, of course, it may be used with other articles. When such an article is sliced in this mechanism, it will be placed in the support 24 and moved inwardly until it engages the plate 21, and as the plate 21 revolves, the knife will proceed to slice the article, one slice being removed during each rotation of the shaft, and the slice, as it is removed, falling through the hole 22 and out at the bottom 27 of the casing.

40 It will be noticed that in cross section, the support is hopper-shaped or, in other words, the bottom is triangular, with downwardly extending sides 28, so that the article being sliced will al-

ways move towards the bottom as its diameter decreases. Conversely, the article will move upwardly away from the bottom as its diameter increases, and in all cases the axis of the article will be substantially normal to the plate 21, so that the slices which are removed will be of substantially uniform thickness; that is, the thickness of each slice will be substantially uniform throughout and will be substantially the same as the thickness of every other slice removed by the same cutter.

The plate is shown as rotating in the direction of the arrow shown in Fig. 2, or in a clockwise direction as viewed in that figure.

15 In advance of the support is disposed a guide 29, the contour of which is best shown in Fig. 4. This guide is in the form of a ridge or lug extending inwardly from the part 16 of the casing and presenting an inclined surface 30 towards the cutter.

20 The knife of the cutter may be formed of thin steel which has more or less resilience and may extend outwardly from the plate a greater distance than is necessary to give the required thickness of the slice. If this occurs, the knife will engage the cam surface 30, and by the time the knife has reached the point 31, it will be in engagement with the edge 25 of the support and will remain in engagement therewith until the slice 25 has been completely removed and until the knife has reached some such position as shown in Fig. 2. By this arrangement, absolute uniformity of slicing is provided.

25 While the plate is shown as mounted substantially concentric with the shaft 11, it may be desirable to mount the plate so that its center is between the knife and the center of the shaft. By this arrangement, a greater lineal speed of the knife is obtained.

30 40 In Fig. 2, I have indicated at 32 in dot and dash lines the outline of an article to be sliced, and, as pointed out above, with the hopper-shaped bottom of the support, the article will be always held with its length substantially normal to a 45 stop formed by the plate 21.

45 I preferably provide a pusher comprising a body 33 (Figs. 5 and 6) and a handle 34. Between the body and the handle may be provided a flange 35, and, if desired, this flange may be so placed 50 as to engage an outer edge 36 of the support when the inner end 37 of the pusher has reached the edge 25 of the support so as to avoid cutting of the pusher by the knife. The body of the pusher conforms generally to the shape of a support, as 55 will be perceived from the drawings.

55 To avoid accidental outward movement of the cutter, I provide on the inner face of the part 16 a projection 38 in line with the shaft 11 and normally engaging the same during operation of 60 the mechanism. This positively prevents movement of the shaft and the cutter secured thereto, and thus aids in fixing the thickness of the slices removed from the article in the support. With 65 the thin knife 23, it is, of course, conceivable that an outward movement of the shaft might otherwise take place, the knife being bent inwardly towards the plate and thus the slices would be made too thin. A similar occurrence is prevented by the projection 38 engaging the shaft 11.

70 Referring now to Figs. 7 and 8, I have shown therein a casing disposed of parts 15 and 16 as before, these parts being fastened together also as before, although such fastening means have been omitted. The similar parts have been given

similar numerals, and their detailed description need not be repeated.

5 In this form, the shaft 11 is used to support a grater comprising a frame 39 supporting a plate 40 which may be spot welded to the support or secured thereto in any other suitable manner. This plate has on its surface a series of protuberances 41 which, as they pass the edge 25 of the support 24, will serve to grate the food in the support 24. The gratings will drop through the 10 bottom 27 of the casing 4.

15 From the above, it will be seen that I have provided slicing mechanism which may be cheaply and efficiently made and easily operated.

15 It is obvious that the part 16 may be first removed and the shaft 11 moved out of engagement with the shaft 4 before removing the part 15. This will be the normal operation with the kind of shaft connection shown herein, although it is, of course, within the scope of my invention to 20 mount the shaft 11 in bearings in the casing part 15, and to use a different type of clutch connection between the two shafts. In that case, the casing could be swung outwardly on its hinges and the entire mechanism removed as a unit after the 25 clutch is disengaged. The form shown, however, has certain advantages, particularly in connection with cleaning the device. As pointed out above, the front part 16 of the casing may be easily removed, and then the shaft 11 with its 30 associated tool, exemplified by the plate 21 or 40 may be removed, it being noted that the shaft 11 passes through a hole in the back of the casing, which is of sufficient size to permit ready movement therethrough of the shaft and its clutch 35 element 13. This arrangement makes a minimum of labor, because it is not even necessary to remove the part 15 of the casing if the device is to be further used.

40 While I have shown the invention as embodied in certain illustrated forms, it is to be understood that various changes in details may be made without departing from the scope of the invention, and I therefore do not intend to limit myself except by the appended claims.

45 I claim:

1. In combination, a power unit comprising a driving shaft having a bore in the end thereof, a casing detachably mounted on said power unit and having an opening in the rear wall thereof 50 in alignment with said driving shaft, a device operating within said casing and having a driven shaft extending through said opening into said bore, cooperating clutch elements on said driving and driven shafts, and a front wall on said 55 casing engaging the end of said driven shaft to prevent its movement out of said bore.

2. In combination, a power unit comprising a driving shaft having a bore in the end thereof, a casing detachably mounted on said power unit 60 and having an opening in the rear wall thereof in alignment with said driving shaft, a device operating within said casing and having a driven shaft extending through said opening into said bore, cooperating clutch elements on said driving 65 and driven shafts, a front wall on said casing engaging the end of said driven shaft to prevent its movement out of said bore, and means detachably holding said front wall in position on the casing, whereby upon removal thereof said device 70 may be removed from the casing and said shaft may be moved through said opening.

ROBERT HOE.
